[57] CLAIM

The ornamental design for shelf for computer keyboard
or the like, as shown and described.

DESCRIPTION

FIG. 1 is a shelf for computer keyboard or the like
showing our new design, a work station being shown
therein in broken lines for illustrative purposes only;
FIG. 2 is a front elevational view;
FIG. 3 is a right side elevational view, the undisclosed
left side being a mirror image thereof;
FIG. 4 is a rear elevational view;
FIG. 5 is a top plan view; and
FIG. 6 is a bottom plan view thereof.

FIG. 2

FIG. 3

FIG. 1

FIG. 4

FIG. 5

FIG. 6
